[57] CLAIM

The ornamental design for an image inputting machine for computers, as shown and described.

DESCRIPTION

FIG. 1 is a top plan view of an image inputting machine for computers showing our new design;

FIG. 2 is a bottom plan view;

FIG. 3 is a front view thereof;

FIG. 4 is a rear view thereof;

FIG. 5 is a right side view thereof;

FIG. 6 is a left side view;

FIG. 7 is a right side view with the paper support shown in a closed position; and,

FIG. 8 is a perspective view thereof.

FIG. 1

FIG. 2

FIG. 3

FIG. 4

FIG. 8
